UNITED STATES PATENT OFFICE

2,437,911

PUMP JACK

Nicholas W. Franzkowiak, Schaller, Iowa

Application July 23, 1945, Serial No. 606,568

4 Claims. (Cl. 74—41)

1

My invention relates to pump jacks.

An object of my invention is to provide an arrangement which can be attached at the top of pumps for reciprocating the pump rod.

A further object of my invention is to provide a readily attachable arrangement for this purpose, and which provides a certain levered operation in which a minimum horsepower is required in using the arrangement.

A further object of my invention is to provide an adjustable arrangement for varying the power stroke as desired, and to provide reciprocation in a straight line.

A further object of my invention is to provide a certain arrangement of supports in combination with the device to provide additional leverage and a bearing rest.

A further object of my invention is to provide an arrangement which is easily assembled and of simple manufacture.

With these and other objects in view, my invention consists in the construction, arrangement, and combination of the various parts of my device, whereby the objects contemplated are attained, as hereinafter more fully set forth, pointed out in my claims, and illustrated in the accompanying drawings, in which:

Figure 1 is a side elevation of the arrangement as used with the pump, and

Figure 2 is an enlarged detail taken along the lines of 2—2 of Figure 1.

I have used the character 18 to designate a standard pump having the spout 11, and an upper bearing plate 12 together with the vertically reciprocating pump rod 13. My invention comprises the bearing plate 14 which is secured to the plate 12 by means of the head screws 15 and attached to the plate 14 are the two vertical cylindrical rods 16 which terminate at 17 in the plate 18 which is secured thereto by means of the nuts

19. Slidably engaged with the vertical rods 16 are the four bearings 20 which merge integrally as a cast unit with the horizontal ribs 21 which ribs extend into the vertical rib 22. Pivotally attached to the ear 23 which is attached to the plate 14 is a bar 24 which is pivoted and secured at 25 to the substantially horizontal lever 26 which lever 26 is pivoted at 27 to the bolt 28 which passes through the pump rod 13 (see Fig. 2) and also passes through the vertical rib 22. Pivotally attached at 29 through any one of the openings 30 at the end of the lever 26 is the substantially vertical lever 31 which is pivoted at 32 eccentrically on the wheel 33 which is driven by means of the shaft 34. The wheel 33 is driven within

2

the casing, 35 by a suitable geared arrangement which is driven from the pulley 36 which pulley 36 is driven by means of the belt 37 passing over a further pulley 38 which is driven by means of the electric motor 39.

The powering arrangement comprising the motor 39, the gears in the casing 35, etc., can be modified to any type, the essential parts of my invention residing in the structure attached to the pump. It will be noted from the foregoing description that the arrangement operates in the following manner. During rotation of the wheel 33 the rod 31 will be reciprocated vertically and due to the attachment of the lever 26 with the frame 21, 22 and the pump rod 13, the pump rod 13 will also be raised and lowered with the bearings 20 sliding upwardly and downwardly along the rods 16. The member 24, with its pivotal attachment at 25, provides a fulcrum for the rod 26 thereby requiring less power for the stroke, which also thereby involves a smaller motor 39. The attachment of the rod 31 to the lever 26 can be made at any of the openings 30 to provide an adjustment for power requirements as well as stroke requirements, and it will be noted as shown in Figure 1 that the power is substantially only one-half of that required for a full length lever since the point of pivoting on the pump rod 13 is about halfway. The arm 24 besides providing a fulcrum effect also provides a constant steady-ing effect during the stroke since at the upper portions of the stroke, the member 24 will travel toward the center of the pump acting as a stabilizing influence at the maximum points. The bearing structure comprising the bearings 20, etc., maintains accurate alignment of the pump rod centrally at all times during its stroke. For repair or adjustment the plate 18 can be removed so that the other parts can also be removed or replaced.

It will now be seen that I have provided the various advantages set forth in the objects of my invention with other advantages being readily apparent.

Some changes may be made in the construction and arrangement of the parts of my invention without departing from the real spirit and purpose of my invention, and it is my intention to cover by my claims any modified forms of structure or use of mechanical equivalents which may be reasonably included within their scope.

I claim as my invention:

1. A pump jack mechanism comprising a lever pivotally attached to the pump rod, said lever having an extending portion, a fulcrum member

pivotedly attached at the extremity of said extending portion, a driving rod pivotedly attached at the other end of said lever, means for driving said driving rod, a framework attached adjacent to said pump rod including a pair of vertical posts attached to the pump, a bearing member slidably engaged with said posts and pivotedly attached to said lever.

2. A pump jack mechanism comprising a lever pivotedly attached to the pump rod, said lever having an extending portion, a fulcrum member pivotedly attached at the extremity of said extending portion, a driving rod pivotedly attached at the other end of said lever, means for driving said driving rod, a framework attached adjacent to said pump rod including a pair of vertical posts attached to the pump, a bearing member slidably engaged with said posts and pivotedly attached to said lever, said posts being parallel to the pump rod, said bearing member including two pairs of spaced sliding bearings each pair of which receives one of said posts.

3. A pump jack mechanism comprising a lever pivotedly attached to the pump rod, said lever having an extending portion, a fulcrum member pivotedly attached at the extremity of said extending portion, a driving rod pivotedly attached at the other end of said lever, means for driving said driving rod, a framework attached adjacent to said pump rod including a pair of vertical posts attached to the pump, a bearing member slidably engaged with said posts and pivotedly attached to said lever, said posts being parallel to the pump rod, said bearing member including two pairs of spaced sliding bearings each pair of which receives one of said posts, means for varying the stroke and power of said lever including a plu-

rality of openings at the end thereof to provide selective attachment of said driving rod therewith.

4. A pump jack mechanism comprising a lever pivotedly attached to the pump rod, said lever having an extending portion, a fulcrum member pivotedly attached at the extremity of said extending portion, a driving rod pivotedly attached at the other end of said lever, means for driving said driving rod, a framework attached adjacent to said pump rod including a pair of vertical posts attached to the pump, a bearing member slidably engaged with said posts and pivotedly attached to said lever, said posts being parallel to the pump rod, said bearing member including two pairs of spaced sliding bearings each pair of which receives one of said posts, means for varying the stroke and power of said lever including a plurality of openings at the end thereof to provide selective attachment of said driving rod therewith, a base plate to which said vertical posts are attached, the lower end of said fulcrum member being pivotedly attached to said base plate, the pivotal attachment of said pump rod, lever, and bearing member being between the upper fulcrum member end and the pivotal attachment of said driving rod and said lever, said lever being normally horizontal.
